UNITED STATES PATENT OFFICE.

CORNELIOUS B. VERONEE, OF ATHENS, GEORGIA.

CLOTHES-BOILER.

SPECIFICATION forming part of Letters Patent No. 252,067, dated January 10, 1882.

Application filed November 24, 1880. (No model.)

To all whom it may concern:

Be it known that I, CORNELIOUS B. VERO-
NEE, of Athens, in the county of Clarke and
State of Georgia, have invented certain new
5 and useful Improvements in Clothes-Boiler At-
tachments; and I do hereby declare the follow-
ing to be a full, clear, and exact description of
the invention, such as will enable others skilled
in the art to which it appertains to make and
10 use the same, reference being had to the accom-
panying drawings, and to letters of reference
marked thereon, which form a part of this
specification.

My invention relates to an improvement in
15 clothes-boiler attachments, and is designed to
provide a device of this character which shall
be of simple and durable construction, of easy
and efficient operation, and capable of being
manufactured and supplied to the trade at a
20 comparatively light cost. With these ends in
view my invention relates to certain details
of construction and combinations of parts, as
will hereinafter be described, and pointed out
in the claim.

25 In the accompanying drawings, Figure 1 is
a view in vertical section of a clothes-boiler
constructed in accordance with my invention.
Fig. 2 is a perspective view of the clothes re-
ceptacle or frame, and Fig. 3 is a plan view
30 thereof.

Let A represent a cylindrical boiler of any
desired diameter and construction, and B an
adjustable hollow cylindrical standard, on the
lower section, B', of which a perforated plate,
35 C, having an upwardly-extending flange, D,
is rigidly secured directly over an imperforate
convex plate, A', having a perforated
depending flange, C'. The upper edge of the
depending flange C' of the convex plate A' is
40 provided with an outwardly-extending flange,
D', which latter fits the boiler-cylinder quite
snugly, and forms an annular chamber, D², be-
tween the flange C' and the inner wall of the
boiler A, connection being made between this
45 annular chamber D² and the space contained
within the imperforate plate A' and its de-
pending flange C' by means of several perfora-
tions, a, formed in the upper part of the
flange C'.

50 Perforated plate C, together with its up-
wardly-extending flange D, forms the recepta-

cle for the clothes, and it is braced and held
from rocking or careening motion when in use
by posts a', the lower ends of which rest on
the outer edge of the convex imperforate plate 55
A', the upper ends supporting the outer edges
of the perforated plate C.

The plates C and A' are mounted on the
lower section, B', of the adjustable hollow cy-
lindrical standard B, the upper section, B², of 6c
which is adapted to fit over the lower section
and have adjustable vertical movement there-
on. Perforations b are formed at the upper
extremity of the section B² of the cylindrical
standard, the open upper end of which is pro-
vided with a device for distributing the heated
water as it comes up through the hollow cylin-
drical standard, said device consisting of a cup-
shaped plate, A², placed in an inverted position
over the top of the section B². 70

A handle, B³, whereby the adjustment of the
cylinder is changed, is secured to the top of
the cup-shaped plate A².

The object of the vertical adjustment pro-
vision of the cylinder is that the device may 75
be adapted to boil large or small quantities of
clothes, using a greater or less quantity of wa-
ter, as the case may be. If, for instance, the
quantity of clothes to be boiled or washed is
small and only a small quantity of water will 80
be needed, the upper section, B², may be tele-
scoped over the lower section, B', and the
heated water will not be required to rise such
a distance before being thrown over the clothes.
An advantage is gained by constructing the 85
perforated plate C with an upwardly-extending
flange, inasmuch as all water discharged
from the upper end of the cylinder must, in
seeking a lower level, pass through the clothes,
as the flange will prevent it from running over 90
the edge of the perforated plate. The clothes
also will, by means of this flange, be prevented
from working over the edge of the said per-
forated plate and escaping the action of the
water. 95

It will be seen that the water, after perco-
lating through the clothes in the receptacle
provided for their reception, runs through the
perforations in the plate C and onto the con-
vex plate A', from which it is discharged over 100
the edge of the flange D' into the annular
chamber D², where it deposits as a sediment

the foreign matter extracted from the soiled clothes. The sediment is deposited between the lower edge of the depending flange C' of the plate A' and the apertures *a* made therein, 5 which latter allow the water to flow into the space under the convex plate A'.

Having thus described the construction of my boiler in detail, I will now proceed to describe its method of operation.

10 The standard, together with its attached parts, is first placed in the boiler-cylinder, and the clothes to be washed are packed in the receptacle provided therefor, and sufficient water, proportional to the amount of clothes in 15 the boiler, is poured thereinto. When, now, the water is heated it will rise in the hollow standard and be showered on the clothes from the upper end thereof. The water will percolate through the clothes and be discharged onto 20 the convex surface of the lower plate, from which it will flow over the edge of the lateral flange at the edge of the said plate, depositing its sediment in the annular chamber formed between the depending flange of the lower plate 25 and the wall of the boiler, and will flow through the apertures *a* into the central part of the boiler, where it will be again heated and passed

through the apparatus in the same manner as described.

I am aware that it is not broadly new to provide a boiler attachment with a cup-shaped plate having a downwardly-projecting flange; nor is it new to provide a central tubular water-passage in combination with the perforated plates of the device. Hence I make no broad 30 claim to those features of construction; but 35

What I claim is—

In a clothes-boiler attachment, the combination, with an inverted-cup-shaped plate provided with a perforated depending flange and 40 a hollow telescopic standard, of a flat perforated plate attached to the hollow standard above the cup-shaped plate, said flat plate provided with an upright annular flange and braces *a'*, connecting the outer edges of the 45 flat and cup shaped plates, substantially as set forth.

In testimony that I claim the foregoing I have hereunto set my hand.

CORNELIOUS B. VERONEE.
